ATTORNEY

UNITED STATES PATENT OFFICE.

THOMAS H. DAILEY, OF CHICAGO, ILLINOIS.

IRRIGATING DEVICE.

1,295,706.

Specification of Letters Patent.

Patented Feb. 25, 1919.

Application filed April 28, 1917. Serial No. 165,203.

To all whom it may concern:

Be it known that I, THOMAS H. DAILEY, a citizen of the United States, residing at Chicago, in the county of Cook and State of Illinois, have invented new and useful Improvements in Irrigating Devices, of which the following is a specification.

This invention relates to an irrigating device which may be employed for internal bathing, the primary object of this character being to provide a device of this character which is especially adapted for flushing the colon and the vagina when desired, and is so constructed as to enable the weight of the person using the same to be employed in increasing the force with which the fluid is injected into the cavities mentioned.

Another object of the invention is to provide a device of this character in which the bag support is of novel construction to permit its ready connection with or removal from the bowls of closets of the type now in common use.

A still further object of the invention is to provide a handle for the injection points associated with the device which is so constructed as to enable the points to be manipulated while in use to insure a thorough cleansing of the cavities without likelihood 30 of the clothing becoming dampened or soiled.

With these and other objects in view the invention resides in the novel combination and arrangement of parts which will be hereinafter described and particularly pointed out in the claims.

The preferred embodiment of the invention has been illustrated in the accompanying drawing, although no restriction is necessarily made to the precise details of construction and arrangement shown, as changes, alterations and modifications within the scope of the claims may be resorted to when desired.

45 In the drawing,

Figure 1 is a top plan view showing the irrigating device connected with the bowl of a toilet in position to be used for flushing the colon.

50 Fig. 2 is a detail longitudinal sectional view through the irrigating device and a portion of the bowl of the toilet, the seat thereof being shown in raised position.

Fig. 3 is a view similar to Fig. 1, showing

the device in position to be employed for flushing the vagina.

Fig. 4 is a bottom plan view of the bag support and showing the same disconnected from the toilet bowl.

Fig. 5 is a detail sectional view through the handle for the injection points.

Like characters of reference denote corresponding parts throughout the several views.

Referring now to the drawing in detail, 65 the letter A designates the bowl of a toilet of the type now in common use upon which is shown mounted the improved irrigating device designated by the letter B, said bowl A having hingedly connected therewith in 70 the usual manner a seat C.

The improved irrigating device includes a bag support 6 which is detachably connected with the rim of the bowl A by means of spaced clamps 7 and 8 mounted upon the 75 underside of the support 6 to engage the rim of the bowl, as shown, the mounting of the clamps permitting adjustment thereof for the attachment of the support to the various types of closet bowls now in use.

A bag 9 formed from any suitable flexible material is provided at one end with a ring 10 by means of which the bag may be connected with the support, and at its other end with a reduced neck in which is removably secured a stopper 12 having connected therewith an end of a hose 13 provided with the usual clasp 14 for controlling the passage of fluid therethrough. A bar or handle 15, which is of greater length than the diameter of the bowl A of the toilet and adapted to rest thereon in a plane parallel to the bag support 6, has formed therein spaced and threaded openings 16 and 17, the opening 17 being arranged adjacent one end of the 95 handle 15, while the opening 16 is formed in the medial portion of the handle.

A pair of injection point holders 18 are removably connected with the handle 15 by means of stems 19 with which the holders 100 are provided, said stems each having a portion thereof extending below the base of its holder 18 and exteriorly threaded to engage the threads in one of the openings 16 or 17 in the handle 15, the lower end of the stem 195 terminating in a nipple 20 for insertion within the outer end of the hose 13, while the other end of the stem 19 provides a

threaded socket 21 in the convex face of the holder 18. A rectal injection point 22 and a vaginal injection point 23 are provided for connection with the respective holders 18.

- 5 When it is desired to use the device for flushing the colon, the bag support and handle 15 are arranged upon the bowl of the toilet, as shown in Figs. 1 and 2, with the rectal point 22 connected with the centrally arranged holder 18. The bag 9 is now filled with fluid and the hose 13 connected therewith attached to the lower end of the stem 19 on the holder 18 with which is connected the rectal injection point 22. The seat C of 10 the toilet is now lowered upon the bag, and the person using the device sits upon the seat with the point 22 inserted in the rectum, the clasp 14 being operated to permit the fluid within the bag to pass through the point 22 and into the rectum by the weight of the 15 person occupying the seat.
- 20 When the colon has become sufficiently distended by the water forced therein, the clasp 14 is operated to shut off the flow of liquid and the injection point 22 withdrawn from the rectum. The handle 15 is now moved forwardly upon the toilet bowl until it contacts with the bag holder 6 which permits the water to be expelled from the colon 25 without interference from the handle.
- 25 When the device is used to flush the vagina, the hose 13 is connected with the stem 19 of the point holder at the end of the handle 15 in which may be mounted the vaginal injection point 23. The seat of the 30 toilet is now lowered upon the bag 10 and the handle arranged at right angles to the bag and bag support, as shown in Fig. 3 of the drawings. The person desiring to flush 35 the vagina now sits upon the seat C with the handle grasped in the hand so that the 40

handle and point may be properly manipulated to insure effective flushing of the vagina.

From the foregoing description, it will at 45 once be apparent that an irrigating device has been provided which may be quickly attached to or disconnected from the bowl of the toilet and is so constructed as to permit the same to be used for the purposes set 50 forth without likelihood of the clothing becoming damped or soiled.

Having thus described the invention, what is claimed as new, is:—

1. An apparatus for the purpose described comprising a support adapted to be superimposed upon the forward portion of a water closet bowl, means carried by said support for detachably fixing it in said position, a compressible bag adapted to be 55 placed upon said support in position to rest under the forward portion of a water closet seat, a handle bar, an injection point carried by said handle bar, and a conduit connection of flexible character interposed between the 60 bag and the injection point.

2. In an apparatus for the purpose described, the combination of a handle bar constructed and arranged to be supported by a water closet, a holder superimposed on 70 said bar, a tubular stem extending through the holder and threaded in the handle bar and extending below the lower side of the latter and having an interiorly threaded enlargement at its upper end counter-sunk in 75 the holder, a hose connected to the lower end of the said stem, and an injection point having a reduced and threaded portion disposed in the upper threaded enlargement of the stem.

In testimony whereof I affix my signature.

THOMAS H. DAILEY.
